UNITED STATES PATENT OFFICE.

HENRY D. PERKY, OF GLENCOE, MARYLAND; LABAN SPARKS, ADMINISTRATOR OF
SAID HENRY D. PERKY, DECEASED, ASSIGNOR, BY MESNE ASSIGNMENTS, TO THE
SHREDDED WHEAT COMPANY, OF NIAGARA FALLS, NEW YORK.

MACHINE FOR MANUFACTURING GRAIN INTO FORM FOR FOOD.

1,022,501.

Specification of Letters Patent.

Patented Apr. 9, 1912.

Application filed March 13, 1906. Serial No. 305,888.

To all whom it may concern:

Be it known that I, HENRY D. PERKY, a citizen of the United States, and resident of Glencoe, in the county of Baltimore and State of Maryland, have made a certain new and useful Invention in Machines for Manufacturing Grain into Form for Food; and I declare the following to be a full, clear, and exact description of the same, such as will enable others skilled in the art to which it appertains to make and use the invention, reference being had to the accompanying drawings, and to letters or figures of reference marked thereon, which form a part of this specification.

Figure 1 is a longitudinal vertical section. Fig. 2 is a transverse vertical section. Figs. 3, 4 and 5 are detail views. Fig. 6 is a vertical sectional view of a modification, showing a speed regulating device.

The invention has relation to machines for the reduction of cereals to filamentous form for food, and it consists in the novel construction and combination of parts, as hereinafter set forth.

The object of the invention is to provide a convenient and economical machine for the purpose, wherein the forming cylinder is designed to serve as a vehicle for drying the product.

In the accompanying drawings, illustrating the invention, the letter *a*, designates a framework, supporting the parts of the machine, and provided at *d*, with bearings for a hollow cylinder *c*, having a perforated cylindrical wall. This cylinder is provided with end flanges *t*, usually of circular form, the flanges being on the outside of the cylinder. The cylinder is designed to be driven by means of a rotary head *e*, provided with a bearing *f*, on which it may rotate and suitable gear teeth *v*, for power connection. Or, it may be geared for operation by hand. The cylinder is designed to be removable from its bearings in the frame, and may be rolled from place to place if desired. It is removably attached to the head *e*, by means of a lug *g*, in order to engage said head for rotation.

The machine is designed to be provided with a press chamber or receptacle *h*, for the reception of the cereal material which is to be fed to the cylinder. Or, the ma-

terial may be inclosed in a charge cylinder *k*, open at both ends. The material is designed to be fed to the inside of the perforated wall of the rotary cylinder *c*, whereby it is molded or formed into filaments which adhere to said cylinder on its outside surface between the flanges *t*.

The material which is preferred for use in connection with this machine consists of grain, deprived of the outer coat or hull, ground, and cooked in a vessel closed in water-tight manner, in boiling water or steam. The material, if corn, in the vessel, is mixed with about its bulk of water, which is designed to be all absorbed in the cooking so that the cooked product will be set in solid form, but will have sufficient plasticity for movement under pressure. The vessel in which it is cooked may be a cylinder having removable caps or ends, and such cylinder should be of proper diameter to fit, neatly, the follower *m*, which is designed to force the material in the cylinder through a throat portion *p*, of the press, which may be located centrally with reference to the driving head *e*, and extend in a direction at right angles thereto. In this case, the throat portion *p*, is of cylindrical exterior, and forms the journal around which the cylinder *c* moves. Or, the throat portion *p*, of the press casing may be located eccentrically, and suitable bearings provided to hold the cylinder *c*, in proper relation thereto, so that the inside surface of its perforated wall will move over the slot-mouth *s*, of the throat in close relation to the marginal bearing *u*, of said mouth.

The follower *m*, is provided with a follower screw *n*, designed to be actuated by means of a gear nut, which may be in adjustable connection with the gearing of the rotary head *e*, which is in engagement with the forming cylinder *c*.

The material being pressed through the mouth or slot *s*, against the perforated wall of the cylinder *c*, while the latter is in rotation, passes through its perforations, forming elongated accretions of filament or tendril form, which accumulate on and around the cylinder between its end flanges until the cylinder is charged, when it may be taken off from the throat portion of the press and transferred to an oven or hot air

chamber for drying the elongated forms, which can then be removed from the cylinder for packing in cartons.

Having thus described the invention, what I claim and desire to secure by Letters Patent is—

1. In a machine of the class described, a removable rolling receiver consisting of a perforated metal cylinder having an open end and provided at its ends with exterior annular rolling flanges of equal diameter adapted to protect the product adhering to the exterior of the cylinder between the flanges.
- 15 2. In a machine of the class described, the combination with a feed press, and a perforated hollow open-end cylinder, of a feed mouth extension within said cylinder, a drive head for the cylinder, and means for simultaneously operating said drive head and said press.
- 20 3. In a machine of the class described,

the combination with a removable perforated cylinder provided with exterior end flanges, a feed press having a throat portion 25 extending within and forming a bearing for said cylinder, a follower device for pressing the material into said throat portion, and means for simultaneously rotating said cylinder and moving said follower, substantially as specified.

4. In a machine of the class described, the combination with a perforated hollow cylinder and a press having a feed mouth forming an inside bearing for said cylinder, of means for simultaneously operating said press and said cylinder.

In testimony whereof I affix my signature, in presence of two witnesses.

HENRY D. PERKY.
